Inventor:

George C. Rueckert
By Horatio E. Bellone
Attorney

UNITED STATES PATENT OFFICE.

GEORGE C. RUECKERT, OF PROVIDENCE, RHODE ISLAND.

JEWELRY TRAY.

Application filed November 8, 1922. Serial No. 599,661.

To all whom it may concern:

Be it known that I, GEORGE C. RUECKERT, a citizen of the United States, residing at Providence, in the county of Providence and State of Rhode Island, have invented certain new and useful Improvements in Jewelry Trays, of which the following is a specification.

My invention relates to jewelry trays adapted for the transportation and display of jewelry mounting cards.

The essential objects of my invention are security of mounting cards against accidental escape; adaptability for removal and substitution of the card retaining frame; and the attainment of these ends in a simple, light, and inexpensive structure.

To the above ends essentially my invention consists in such parts and in such combinations of parts as fall within the scope of the appended claims.

In the accompanying drawings which form a part of this specification,

Figure 1 is a plan view of the device embodying my invention,

Figure 2, an enlarged fragmentary top plan view of a corner of the same,

Figure 3, an enlarged bottom plan view of the retaining frame,

Figure 4, a fragmentary section on line 4—4 of Figure 1,

Figure 5, a section on line 5—5 of Figure 3, and

Figure 6, a perspective view of the slotted end of a cross bar.

Like reference characters indicate like parts throughout the views.

My device includes a tray or box, either open or closed, comprising side walls 8 and end walls 9. Glued or otherwise fixed to the walls is a floor 11 preferably of soft fabric, also fast to bottoms of the walls are thin guide strips 12 preferably of fiber or metal and spaced above the floor. In this case the floor and guide strips are attached to the walls by nails 13.

Detachable mounted in the box is a retaining frame comprising longitudinal bars or strips 15 and transverse bars or strips 16 intersecting each other. Each bar 15 comprises a flat base portion 17 and a central elevated rib portion 18. In this instance an intermediate part of the base portion 17 is omitted. Each bar 16 comprises a base 20 and rib 21 respectively. One end of each

bar 16 is undercut to form an inwardly extending slot 22 as shown in Figure 6. These slots are purposed to receive the strips 12. The bars 15 and 16 are of lengths to respectively abut lightly at their ends against the walls 9 and 8.

The rigid and rectangular character of the frame does not permit entire engagement of the frame by the slot construction. For this reason the following auxiliary detachable fastening means has been devised. Upon one or more of the bars 16, in this case three, near their ends opposite to the slotted ends are pairs of clips or locking plates 24 disposed side by side on the base at opposite sides of the rib. In detail each plate is of thin stiff material, in this case of steel, and is approximately quadrant shaped comprising a portion 25 extending laterally of the bar to which it is attached and a free end 65 portion 26 disposed at right angles to the lateral portion and extending longitudinally of the bar and parallel to the latter. The member 24 is pivoted upon the bottom of the base 20 and is provided upon its outer 80 edge with a notch 27. Near its inner end each portion 25 is provided with a perforation 28 through which loosely passes an eyelet 29 tight in an opening 30 in the base 20 at one side of the rib 21. The ends of the 85 eyelet are upset to form flanges 32 and 33 engaging the clip and base respectively. The member 24 has pivotal action on the member 29.

To introduce the frame into the box the former elevated at a slight angle is moved so that one strip 12 enters the slots 22. The frame is now dropped into a horizontal plane with the ends of the rods 16 opposite the slotted ends resting upon the other strip 95 12. Meanwhile all the members 24 are in retracted position. This position of a single locking plate is shown in broken lines in Figure 2. Next, the operator inserts his finger nail in the cavity 27 of each locking 100 plate and pushes the latter forwardly so that its outer end slides between the strip 12 and the floor 11, where it is frictionally held.

The cards or pads to which the articles of jewelry or novelties are fixed rest in compartments of the retaining frame.

It is also to be understood that the language used in the following claims is intended to cover all of the generic and specific features of the invention herein described,

and all statements of the scope of the invention which, as a matter of language, might be said to fall therebetween.

I claim:

- 5 1. In a jewelry tray, a rectangular box having walls, and a floor secured to the walls, strips upon two opposite walls extending above the floor, a retaining frame comprising longitudinal bars and intersecting transverse bars, said transverse bars being provided with slots in their ends adapted to loosely receive one of the strips, and having their opposite ends resting upon the other strip, and locking plates pivotally mounted upon the transverse bars adjacent their ends slidably engaging the second strip.
- 10 2. In a jewelry tray, a rectangular box
- 15

having walls, and a floor secured to the walls, strips upon two opposite walls extending above the floor, a retaining frame 20 comprising longitudinal bars and intersecting transverse bars, said transverse bars being provided with slots in their ends adapted to loosely receive one of the strips, and having their opposite ends resting upon the 25 other strip, and angularly disposed locking plates pivotally mounted at their inner ends upon the transverse bars and having their outer ends so disposed as to move beneath the other strip, said locking plates being 30 provided with lateral cavities.

In testimony whereof I have affixed my signature.

GEORGE C. RUECKERT.
